UNITED STATES PATENT OFFICE

2,233,710

WHEELBARROW

George O. Osterkamp, Burbank, Calif.

Application June 12, 1939, Serial No. 278,596

1 Claim. (Cl. 280—52)

This invention relates to a wheeled vehicle and particularly pertains to a wheelbarrow.

In transporting materials from place to place, such for example as concrete, cement and grouting, it is desirable to utilize a wheelbarrow within which the material may be carried and from which the material may be poured in a manner to insure accurate placement of the material with a minimum loss by spilling. Wheelbarrows of this particular type are used to transport materials from a cement mixer or the like to a point where they are poured out and placed. It is the principal object of the present invention to provide a wheelbarrow which will carry a maximum load and which is formed with a body having a particular pouring spout at its forward end so that material may be directly placed when the wheelbarrow is dumped.

The present invention contemplates the provision of a wheelbarrow having the conventional running gear and a body portion of scoop shape formed with a pouring spout at its forward end and overhanging the wheel and from which spout the material may be accurately poured.

The invention is illustrated by way of example in the accompanying drawing, in which:

Figure 1 is a side view of a wheelbarrow showing the details of the body structure.

Fig. 2 is a view in plan showing the wheelbarrow and the spout formation.

Fig. 3 is a view in end elevation showing the form of the pouring spout.

Referring more particularly to the drawing, 10 indicates a wheel carried upon an axle 11 and mounted in bearings 12 of a wheelbarrow frame 13. This frame is formed with a pair of shares or handles 14 by which the load may be lifted and by which the wheelbarrow may be moved from place to place. Suitable legs 15 are provided to support the frame. Mounted upon the frame structure 13 is a wheelbarrow body 16. This structure is characterized by having a pouring spout 17 at its forward end. The body structure is formed with a floor 18 bounded on its three sides by side walls 19, 20 and 21. The body portion 18 is formed with a forwardly and upwardly extending floor 22 along opposite sides of which side wall sections 23 and 24 occur. These sections are continuations of the side walls of 19 and 21, respectively. At the forward end of the floor continuation 22 a throat 25 is formed. This throat is defined by a transverse edge 26 of the floor 22 and the side members 23 and 24, as particularly shown in Fig. 3 of the drawing. It is to be understood that the exact

design of the body structure 16 may be changed to accommodate the requirements as to the material to be hauled and the manner in which it is to be placed, and that the invention is particularly concerned with the provision of the pouring spout 17 which extends forwardly and above the wheel 10 and is formed with a throat 26 having side walls 23 and 24 to direct the material from the wheelbarrow through the throat to a desired point of placement.

By reference to Fig. 1 of the drawing it will be seen that the portion 18 of the floor stands substantially horizontal and that the floor extension 22 extends upwardly and forwardly therefrom while the back wall 20 extends upwardly and rearwardly, and the side walls 19 and 21 flare upwardly and outwardly. This provides a pan-like structure of considerable capacity in which material may be placed. It will also be noted that the upper edges of the side walls 19 and 21 extend upwardly and forwardly, as indicated at 27 in the drawing, and lie in a plane which is indicated by the dotted line 28, and which plane extends forwardly to the edge 26 of the floor portion 22. The continuing portions 23 and 24 of the side wall converge toward the throat 25 and project upwardly above the plane occupied by the edges 27 of the side walls and the edge 26 of the pouring spout. This provides guide walls which confine the material and permit it to be poured out of the spout.

In operation of the wheelbarrow as here described the device is constructed as shown and described, after which the material to be hauled is placed within the body portion 16. When it is desired to discharge the material therefrom the wheelbarrow may be lifted to swing the pouring spout 17 forwardly and over the wheel 10 and to allow the material to pour outwardly as guided through the throat 25.

It will thus be seen that the wheelbarrow here described while simple in construction, provides a desirable feature not present in wheelbarrows as now made, in that the body of the wheelbarrow will accommodate a large volume of material which may be transferred from place to place without spilling, and for the further reason that when it is desired to pour material from the wheelbarrow this may be accomplished easily while directing the material accurately to a point of placement.

While I have shown the preferred form of my invention as now known to me, it will be understood that various changes may be made in combination, construction and arrangement of parts

by those skilled in the art, without departing from the spirit of my invention as claimed.

Having thus described my invention, what I claim and desire to secure by Letters Patent is:

5 A wheelbarrow having a frame, a running gear wheel at the forward end thereof, a pair of shares extending from the rear thereof, a body member mounted upon said frame and extending forwardly and upwardly over the running gear wheel, the body member having a relatively narrow floor of substantially uniform width comprising a horizontal portion and an upwardly and forwardly extending continuation thereof

to a point above the running gear wheel, a back wall extending upwardly and rearwardly from said floor, outwardly and upwardly flaring side walls at opposite sides of the horizontal portion of said floor and outwardly and upwardly tapering side 5 walls forming continuations of the first named side walls with their upper marginal edges converging toward the forward edge of the upwardly inclined floor portion and terminating above the side edges of the upwardly and forwardly extending floor section whereby a pouring throat will be formed by said floor and side walls.

GEORGE O. OSTERKAMP.
